UNITED STATES PATENT OFFICE.

HARLEY B. McELYEA, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

BANK AND TRUNK CABLE MULTIPLING SYSTEM.

Application filed December 18, 1922, Serial No. 607,485. Renewed December 4, 1926.

The present invention relates to bank and trunk cable multipling systems in general, that is, systems for multipling together the bank cables of selector switches and the trunk cables leading to the switches in the next series in automatic telephone systems; and the main object is the production of an improved system of the above named type, whereby the bank and trunk cables in an automatic telephone system may be readily multiplied together in any desired manner, and may be later multiplied together readily in any other manner as the necessity arises.

Another object, incidental to the carrying out of the main object, is the production of a new and improved distributing frame for use in connection with the improved multipling system which may be manufactured cheaply; which is simple and easy to install; and which permits the bank cables to be connected together in either large or small groups, or in any one of a large number of different combinations, with a minimum amount of labor.

It is common practice in automatic telephone exchanges employing step by step selector switches of the vertical and rotary type to place the switches side by side in shelves or rows of ten or twenty switches each, and to multiple the bank contacts of adjacent switches together in groups of ten, the banks being multiplied so that corresponding contacts are wired together throughout the ten switches of any one group. A plurality of switches with their banks so multiplied are known in the art as a "shelf". It is also common practice to multiple a trunk cable to corresponding levels in a plurality of shelves of switches in order to secure the correct amount of traffic for the switches to which the trunk cable extends.

It is very evident that when the above-named practice is followed, some sort of connecting frame or terminal assembly must be provided if the multipling wires are not to become a hopeless tangle. According to the practice which has been commonly followed heretofore, two suitably constructed parallelogram shaped mounting frames are placed in an upright position about two feet or more apart and parallel to each other. The switches are placed on these frames in five or six horizontal rows with one row above another and with two shelves of ten

switches each in each row. A connecting cable, or "bank cable" as it is called, connects the banks of each shelf of switches to the terminal assembly frame which is placed in an upright position across one end of the space between the mounting frames. The word "bay" is commonly used to mean a group of shelves of switches collectively that are connected by their bank cables with a common terminal assembly frame.

On the terminal assembly frame the bank cables are connected to flat terminals which are secured in long strips of insulating material laid on the horizontal supports of the terminal assembly frame. The multipling together of adjacent shelves is taken care of by so-called up and down multiples. An up and down multiple, it may be stated, comprises two flat terminal strips, similar to the terminal strips to which the bank cables are connected, and a connecting cable.

When one shelf is to be multiplied with another shelf, its terminals and one set of terminals of an up and down multiple are soldered together. The terminals of the other shelf are secured in like manner to the terminals of the other strip of the same up and down multiple, and also to still another multipling strip if a third shelf is to be included in the multiple. This process is repeated until the desired number of shelves are multiplied together. The number of shelves, of course, that are multiplied together is determined by the traffic conditions and often varies considerably among the different levels.

The outlets for a shelf or for a group of multiply connected shelves are provided by trunk cables which also are terminated on the supports in flat terminals. These terminals are bent into engagement with and soldered to the terminals of the desired shelf or to the terminals of one shelf of a multiply connected group of shelves.

While the foregoing method of multipling together the shelves and of providing outlets for the traffic has been successfully used for a number of years, it has been found to be inflexible as regards traffic changes which occur more or less frequently, and also as regards additions which involve regrouping and rearranging. These facts and others of varying importance have presented themselves and have given rise to the development of a distributing frame to re-

place the old terminal assembly frame. This distributing frame is exceedingly flexible as regards traffic changes and as regards regrouping necessitated by additions which are likely to occur from time to time.

When the new distributing frame is used, it occupies the same relative position as the old terminal assembly frame, and comprises essentially bank cable terminal blocks which 10 are arranged in horizontal strips and occupy the greater part of the space on the frame, and trunk cable terminal blocks which also are arranged in horizontal strips and occupy the upper part of the frame. The terminals 15 in both the bank cable terminal blocks and the trunk cable terminal blocks are of the pin type.

The up and down multiplying, or the multiplying between adjacent shelves, is taken 20 care of by bare jumper wire which extends vertically along the front of the distributing frame, and which is soldered to corresponding contacts on the various blocks which are to be multiplied together.

25 The rear end of each bank cable terminal block pin has two notches instead of one. The bank cable wire is fastened to the pin at one notch, leaving the other notch free so that a jumper wire can be fastened to the pin to connect the multiplied group with an outgoing cable to which access is gained through one of the trunk cable terminal blocks in the upper part of the frame.

30 Referring now to the drawings comprising Figs. 1-10, inclusive they show various views of the new distributing frame, and also serve to give an understanding of a few of the many ways in which the improved distributing frame can be used.

35 Figure 1 is a view, drawn to a considerably reduced scale, showing a mounting frame fully equipped with twelve shelves of switches and also an edge view of the new distributing frame, which frame serves as a 40 distributing frame for the switches shown, and also for an equal number of switches 45 similarly located on a mounting frame behind the one shown and parallel to it.

Figure 2 is a front view of the improved 50 distributing frame and shows the bank cable terminal blocks and the trunk cable terminal blocks in place, the trunk cable terminal blocks being those in the upper section, and the bank cable terminal blocks being 55 those in the lower section.

Figure 3 is drawn to a larger scale than Figs. 1 and 2, and is a view of the section of the distributing frame which is separated from the major part by the dotted line 3-3, 60 Fig. 2.

Figure 4 is a rear view of the section shown in Fig. 3 with one bank cable 31 and one trunk cable 55 shown in place.

Figure 5 is a view of the improved 65 distributing frame and the first five vertical

rows of switches on either side, as seen from the top, with the frame-work shown above the dotted line 5-5, Fig. 1, removed in order to give a clearer view.

Figure 6 is a top view of a bank cable 70 terminal block and is, for example, one of the blocks shown in the strip 53, Fig. 3. This block is drawn to actual dimensions.

Figure 7 is a view showing more clearly the construction of a single terminal, such 75 as one of the terminals in the block shown in Fig. 6.

Figure 8 is a diagrammatic view of the improved distributing frame, and shows in one particular situation the number of 80 shelves which are multiplied together on the various levels and are jumpered to the desired trunk cables.

Figure 9 is a diagram of a second distributing frame interconnected with the 85 first by tie cables.

Figure 10 is a detailed diagram and shows an alternative method of connecting up the fourth level of bank contacts at the 90 distributing frame shown in Fig. 8.

While the improved distributing frame may be used in connection with any desired 95 automatic switch, the switches shown in Figs. 1 and 5 are assumed to be of the type described in connection with and shown in Fig. 62 of the illustrations in the second edition of Automatic Telephony, a book by Smith & Campbell, published by McGraw-Hill Book Company, Inc., New York. A photograph of selectors covered and mounted as indicated in Figs. 1 and 5 is shown in Fig. 98 of the above mentioned book.

In view of the illustrations above referred to, it is considered unnecessary to 105 show the switches in any detail and, consequently, they are indicated only generally. However, the shaft and wipers of switch 20, Fig. 1, and also of the switch in the lower left-hand corner of the same figure, are indicated to give some slight idea of how the 110 switches look.

Referring now particularly to Figs. 1-7, inclusive, the construction of the improved distributing frame and its position as regards the associated switches and switch 115 banks will be explained. The frame on which the switches shown in Fig. 1 are mounted, comprises essentially three suitably braced uprights, and the interconnecting cross-bars on which the switches are hung. Of the three switch supporting uprights, only two, 46 and 47, are visible. The other one is directly behind the upright 45 and in line with the uprights 46 and 47, the uprights 45 and 48 being located far enough forward to allow the front part of the switches to come behind them so that doors may be provided if desired. The relative positions of the uprights may be readily ascertained upon reference to Fig. 5 which,

as before stated, is a top view of the distributing frame and the first five vertical rows of switches.

The distributing frame, seen most clearly 5 in Fig. 2, comprises essentially the uprights 48 and 49 and the strips of terminal blocks which are secured between them.

The switch mounting frame shown in Fig. 1, the one behind it, and the distributing frame are bound together at the top by the four strips of heavy angle irons 41-44, 10 inclusive.

Taking the top row of switches shown in Fig. 1 for example, the first ten switches, 15 1-10, inclusive, comprise a shelf and their banks are accordingly multiplied together and are connected with the distributing frame by the cable 31.

The banks of the shelf of switches comprising switches 11-20, inclusive, are connected with the distributing frame by the cable 32. The other shelves of switches below are similarly connected as is indicated by the other cables.

20 As shown, the bank cables from the two shelves in the top row of Fig. 1 lead to the first two bank cable strips 53 and 54, Fig. 2; the two bank cable strips immediately below are left for the cables coming in from the other side of the distributing frame; and the next two shelves of switches from the top, Fig. 1, are associated with the fifth and sixth bank cable strips, etc. This arrangement, however, is merely arbitrary 25 and may be deviated from as desired. For example, the arrangement may be such that the two top shelves, Fig. 1, may be cabled to the first and third strips, leaving the second and fourth strips for cables coming 30 in from the other side of the distributing frame.

The four strips located at the top of the distributing frame, Fig. 2, represent terminal blocks to which the trunk cables which 45 form outlets for the traffic from the associated switches are connected. As shown, there are five blocks in each strip, making twenty blocks in all. The terminals in each 50 of these blocks are arranged in twenty sets and each set contains three terminals, as indicated in Fig. 5. The above arrangement of terminals for the trunk cables is the usual one. However, when desired, room for more trunks is provided by using so-called six-pin blocks instead of the three-pin blocks shown.

The conductors of the trunk cable are connected to the lower end of the trunk block terminals as is indicated by the position of cable 55, Fig. 4, and when the cables are connected, each set of three terminals represents one three-conductor trunk.

Referring now particularly to Figs. 3, 4, and 6, it will be noted that the terminal blocks of a bank cable strip are secured be-

tween two parallel angle irons such as 62 and 63, Figs. 3 and 4, by bolts such as the bolts 64 and 65, which fit into grooves in the ends of the blocks, which grooves can be seen most clearly in Fig. 6. This permits 70 a block to be removed by merely removing one of the two bolts which hold it in place. The parallel angle irons between which the bank cable blocks are secured, are in turn secured by bolts between the upright angle 75 irons 48 and 49, as can be seen most clearly in Fig. 4.

Although any one of a number of different methods may be used in placing the pins in the bank cable terminal blocks, such as 80 using sectional blocks and blocks with holes in them, etc., the preferred construction is that the bank cable terminal blocks are molded composition, such as hard rubber for example, and that the blocks are molded 85 around the terminals.

It will be noted, upon reference to Figs. 3 and 4, that the terminals in a bank cable block are arranged in ten groups of three, one terminal above the other. However, 90 the terminals are so staggered that no one terminal is directly above any other terminal in the same block, but is directly above the corresponding terminal in the block below. This permits any desired number of contacts located in a vertical line to be multiplied together in a neat workmanlike manner with uninsulated wire. The front of each of the terminals, as is seen best in Figs. 6 and 7, is 95 grooved so as to allow the bare jumper wire 100 to be centered on the terminal without difficulty, and also to facilitate the soldering of the jumper wire to the terminal. A few of the bare jumper wires are shown in place 105 and soldered in Fig. 3.

Referring now particularly to Figs. 4, 6, and 7, it will be noted in Fig. 4 that the conductors of the bank cable 31 are connected to the terminals at the rear of the bank cable terminal blocks. As shown in Figs. 6 and 110 7, two sets of notches are provided for each terminal. One set of notches is for the bank cable which is placed on first, and which is connected to the notches nearer the block, and the other set of notches is for the 115 jumpers which are run from certain of the bank cable blocks to the correct trunk cable block in the upper part of the distributing frame. The jumpers are passed up from underneath through the desired one of the five holes in the spreading strip such as the spreading strip 61, which is to be seen most clearly in Fig. 6. The ends of two jumpers 74 and 75 are shown in Fig. 4. The remaining part of the jumpers cannot be shown in Fig. 4 for the reason that they pass back through jumper rings in a manner similar to the jumpers shown in Figs. 1 and 5.

It may be seen that when the new distributing frame is used, as many shelves as de- 130

sired may be grouped together by multiplying the corresponding terminals on the front of the distributing frame with bare wire, and that the group thus formed can be connected to the desired trunks by means of jumpers. With this arrangement, the up and down multiple on the front of the distributing frame may be varied so as to include more or less shelves of switches as the occasion demands, and the jumpers which connect the groups of shelves to the trunk cables may be changed accordingly at will.

Referring now particularly to Fig. 8, which as before stated, is a diagrammatic view of the improved distributing frame, the associated shelves of switches are indicated by the thin horizontal rectangles on either side, which are lettered A to L, inclusive, and A' to L', inclusive. The heavy lines which are below the rectangles representing the switches, represent the banks of the switches, and the lines which connect the switch banks with the horizontal rows of short heavy lines located in the middle of the drawing represent the bank cables.

One short heavy line in any horizontal row to which a bank cable connects indicates one complete bank cable terminal block, and is connected by the bank cable to one level of contacts in the associated shelf of switches. The bank cables, of course, are so fanned out and connected, that the first block in each strip is connected with the first level of bank contacts and so on to the tenth block, which is connected with the tenth level of bank contacts as is indicated by numerals placed under the vertical rows of blocks at the bottom of the drawing. The order in which the shelves of switches are connected to the strips of terminals in Fig. 8, it may be stated, is the same as is indicated in Fig. 2 by the letters A-L, inclusive, and A'-L', inclusive, placed opposite the bank cable terminal strips.

Regarding the trunk cable terminal blocks shown above the bank cable terminal blocks, it may be said that these blocks are connected up by trunk cables to the switches in the proper groups in such a manner that the group connected with the first vertical row of blocks is group No. 1, and so on in order corresponding with the bank levels which are underneath. This arrangement, however, is purely arbitrary and may be varied to suit the requirements of any particular installation. It will be noted that ten vertical rows of trunk cable terminal blocks are indicated, while only five vertical rows are shown in Fig. 2. The reason for this seeming discrepancy is that one short heavy line in Fig. 8 indicates only half of one complete block as shown in Fig. 2, because one block contains twenty sets of contacts which is sufficient for two levels. Also, it will be noted that there are more horizontal rows of

short horizontal lines indicating trunk cable terminal blocks than there are strips of blocks indicated in Fig. 2. This is due to the fact that when as many blocks are needed as are shown equipped in Fig. 8, some of the blocks shown in Fig. 2 must be provided with six terminals in a set instead of three, in which case that block is indicated by twice the usual number of short heavy lines. No attempt has been made to indicate which of the strips of blocks shown in Fig. 2 are equipped with six terminals in a set for the reason that any strip may be so equipped without altering the scheme.

It will be noted that certain of the spaces in the section allotted to the trunk cable terminal blocks are left blank. This is done because there are no cables at present on these blocks. However, the terminals may or may not be on the blocks at those places, depending upon whether or not there is a likelihood that they will be needed in the future.

The two upper rows of heavy short lines indicate the blocks to which tie cables are connected, so as to link the distributing frame shown in this drawing with the one shown in Fig. 9, for a purpose that will appear more fully as the description progresses.

For the purpose of this description, it will be arbitrarily assumed that the distributing frames shown in Figs. 8-10, inclusive, are serving second or thousands selectors in one office of a multi-office system with an ultimate capacity of ten offices. Accordingly, the switches shown in Figs. 8 and 9 are required to select any one of a plurality of groups of a thousand lines each. It will be assumed further that the traffic differs considerably amongst the various thousand line groups, and that the ninth and tenth levels are dead for the reason that the corresponding groups are left blank.

It will be assumed further that if the traffic were equally divided amongst the eight working levels, seven shelves multiplied together on the working levels would form a group of the proper size and with the proper margin of safety to furnish traffic on any one level for ten trunks. Since, however, according to a previous assumption, the load is not equally divided amongst the eight working levels, the arrangement is varied so that we have in some cases more than seven shelves multiplied together on one level and less than seven multiplied together on another level. For example, on the first and sixth levels, where the traffic is relatively light as compared with the other levels, eight shelves can be multiplied together and jumpered to one trunk cable as is indicated by the bundles of jumpers represented by the three lines bearing the reference characters 279-281, inclusive, which connect the three groups of eight shelves each of the first level

to the three trunk cables in the corresponding vertical row. In order to avoid complicating the drawings, no lines have been run to represent the other bundles of jumpers, but instead, the numbered circles have been provided to indicate corresponding points between which the ten jumpers should be run. As an example, a bundle of ten jumpers should be run between two points indicated by the two circles numbered 113.

It is assumed that the traffic is comparatively heavy on the fourth and fifth levels, which may be the case if the corresponding thousands groups handle a considerable amount of private branch exchange traffic or contain a larger than usual proportion of business lines. Accordingly, only six shelves can be multiplied together on these two levels in order to furnish all the traffic that can be safely carried by ten trunks. Each of the other four working levels, 2, 3, 7, and 8, carries the average amount of traffic and, accordingly, seven shelves are multiplied together on these levels. Since, there are twenty-four shelves associated with the distributing frame and, since twenty-four is not a multiple of seven, the shelves do not come out even, and the grouping must be extended to the distributing frame and associated switches shown in Fig. 9 by way of the series tie cable 272. Taking the second level, for example, three complete groups of seven shelves each are formed on the distributing frame shown in Fig. 8 and the three bottom shelves are left over. The three bottom shelves are strapped together with the bare wire jumpers in the usual manner, and the ten jumpers are run to the proper trunk cable as is indicated by the two circles numbered 104. Another set of ten jumpers is then run from one of the multiply connected shelves in the partially formed group between the points indicated by the circles numbered 105. Since, four shelves are required to complete the group, the first four shelves shown in Fig. 9 are strapped together on the second level, and the jumpers indicated by the circles numbered 154 are run from the second block to one of the bank cable terminal blocks of the four multiply connected shelves, thereby completing the group of seven shelves which is located partly in one bay and partly in another bay. As can be seen, each of the other three levels 3, 7, and 8 are taken care of in a similar manner. When the bottom of the distributing frame shown in Fig. 9 is reached, it is found that the shelves come out uneven again and, accordingly, the partially completed group is carried over to the next bay, not shown, through the series tie cable which extends to the next bay. This is carried out until the group comes out even, or until the last bay is reached and, if

a partially filled group is encountered on the last bay, it may be taken care of by interconnecting it with one or two of the preceding groups or by any other well-known expedient, such as reducing the number of switches to which it has access and making the remaining contacts artificially busy.

It is the usual practice, when one or more levels of a selector are dead, to multiple the contacts together throughout several bays or in some instances throughout all the bays of selectors in the office, and to connect the group to an operator by way of a few so-called dead level trunks. Accordingly, the ninth and tenth levels on the distributing frame shown in Figs. 8 and 9, are strapped together from the top to the bottom, and the two levels are multiplied within each bay by a set of jumpers which are shown on the bank cable terminal blocks of the shelves B and B², respectively. It is assumed that the trunk cable with which one of the circles 132, Fig. 8, is associated, is the one containing the dead level trunks and, consequently, the bundle of jumpers which is run between the points indicated by the two circles 132, provides an outlet for any calls which may land accidentally on the ninth and tenth levels in this bay. These dead level trunks are multiplied over to the remaining bays through the multiple tie cable which is connected to the top set of terminal blocks through the bundle of jumpers indicated by the circles 133. The dead levels in the other bays are jumpered to the corresponding blocks of the multiple tie cable and are thereby connected with the dead level trunks. For example, the ninth and tenth levels of the bay shown in Fig. 9, are connected with the multiple tie cable by a bundle of jumpers indicated by the circles 185.

Referring now particularly to Fig. 10, which as before stated, is a detailed diagram showing an alternate method for combining several shelves of switches so as to enable the outgoing trunks to handle the same number of calls with fewer lost calls or a larger number of calls with the same percentage of lost calls, this is a specific cross-connecting diagram and is shown merely to illustrate the amount of flexibility that can be secured with the improved distributing frame and, therefore, a specific case must needs be assumed. Accordingly, it will be assumed that this diagram represents the fourth level of bank contacts connected to the distributing frame shown in Fig. 8. In this drawing, one short heavy line indicates a set of three contacts, one horizontal row of short heavy lines in the lower section indicates one bank cable terminal block, and one horizontal row of short heavy lines in the upper section represents a section of trunk cable terminal block to

which ten trunks extending to a shelf of switches in the next series is connected.

It is well-known that selector switches of the home position type such as are assumed to be used in connection with the improved distributing frame, always seize the first trunk to which they have access if it is idle, and if it is busy, test the next one and so on, always taking the first idle trunk.

10 That being the case, it is natural to expect that the first trunk will be in use more of the time than any one of the others and that the trunks in order from 2 to 10 will each handle fewer calls than the preceding one.

15 This is what proves out in practice and is an established fact. It is known also that if the trunks can be combined into groups of more than ten each, say twenty, the larger groups are more efficient and, accordingly, 20 the average number of calls handled per trunk is greater.

Referring now again to Fig. 10, the trunks accessible from the level of contacts shown there are combined into two groups 25 of twenty trunks each instead of four groups of ten trunks each as shown in Fig. 8, thereby permitting the two groups to handle the traffic with a better margin. The way in which the trunks are combined in the 30 groups will now be explained. The first five contacts of the shelves on this level are strapped together in six sets of four, and the last five contacts are strapped together in two sets of twelve. This means that any 35 four shelves, the first four for example, have five trunks which are first to fifth choice to these four shelves, and which are not accessible to any other switches, and that these four shelves together with two other groups 40 of four shelves each have common access as sixth to tenth choice to the five trunks which are multiplied to the first twelve shelves and which are used only when all the trunks individual to a group of four shelves 45 are in use.

This arrangement, so far, is the usual common and individual trunking scheme. However, with the type of distributing frame commonly used heretofore, it has been impractical to divide the traffic on the outgoing trunk cables so that the various shelves of switches in the succeeding series all carry practically the same amount of traffic. For 50 example, if one shelf of switches in the succeeding train handles the traffic from five individual trunks and five common trunks while another shelf of switches handles traffic from ten individual trunks, the traffic on the second mentioned shelf of switches will 55 be very much greater than the traffic on the first shelf, and it will, consequently, be very difficult to figure out the correct way to multiple the various shelves together of the succeeding series of switches in order to 60 load the cables outgoing therefrom prop-

erly, and will involve much calculating and checking in order to distribute the load properly. However, when the improved distributing frame is used, the jumpers can be run to the desired set of terminals, and the load can be easily balanced between the two shelves of switches which carry the traffic from one group of twenty trunks. For example, it can be seen that the trunk cable coming from the lower trunk cable terminal 75 block carries the traffic from the first five contact sets of the first four shelves; that it carries the traffic from the sixth, seventh, and ninth contact sets of the first twelve shelves; and that it carries the traffic from 80 the third and fifth contact sets of the second four shelves. These ten trunks according to a careful calculation, upon which it is unnecessary to dwell here, carry approximately half the traffic on the group of 85 twenty and, consequently, the traffic carried by the cable which is connected to the next trunk cable terminal block above will carry approximately the same traffic for the reason that it takes care of the ten remaining 90 trunks of the group.

The remaining shelves in this bay are similarly strapped and jumpered on the level in question, so as to form a second group of twenty-trunks, the jumpers being 95 omitted in order to avoid complicating the drawings. The places to which the jumpers are connected are indicated by the circles which are numbered in pairs from 201 to 220, inclusive.

In order to even up the traffic amongst the various trunks in each group of five individual trunks, the first five trunks in each alternate shelf of switches, beginning with the "B" shelf, are reversed as may be 100 seen upon referring to the numerals applied to the contacts. For example, the first set of contacts on the distributing frame which is connected with the "B" shelf is connected with the fifth set of contacts of the switches, 110 as is denoted by the numeral 5 associated therewith, while the fifth set of contacts appearing on the distributing frame which is connected to the "B" shelf, is connected with the first set of contacts in the banks 115 of the switches in the "B" shelf.

The last five trunks of each bank cable are connected straight on the distributing frame, that is, the sixth trunk is sixth choice, the seventh trunk seventh choice to 120 all the switches, etc. If desired, however, the sixth to the ninth trunks, inclusive, may be reversed in each alternate shelf in case the situation demands it.

The tenth trunk under normal conditions 125 handles very little traffic, being used only when five trunks in some individual group are busy and when the four preceding common trunks are busy. Under the arrangement contemplated, the tenth trunk is last 130

choice to all the switches, so that a meter may be associated with the tenth trunk and will indicate quite accurately whether or not the group of twenty trunks is properly loaded. For example, if the meter associated with the tenth trunk shows a very small number of calls or none at all for a given time, the indication is that the group of twenty trunks is loaded too lightly. On the other hand, if the meter indicates that the tenth trunk handles a large number of calls in a given time, the group may be overloaded to such an extent that a great many calls are lost for the want of a sufficient number of trunks.

Regarding the multiple tie cable shown in Figs. 8 and 9, it may be said that this cable is used principally in making changes in the amount of traffic supplied to the various trunk cables after an exchange is installed and is seldom used to any great extent initially. As shown, this cable takes care of the dead level multiples between the "bays" shown in Figs. 8 and 9, and the other "bays" in the same group, as is indicated by the bundles of jumpers which are assumed to be run between the circles numbered 133 and 185.

According to a foregoing assumption, the selector switches associated with the distributing frames indicated in Figs. 8 and 9 are thousands selectors in a multi-office system and, accordingly, certain ones of these selectors are reached by office selectors in the local office, while the others are reached by way of the office selectors in the other offices of the system. It commonly occurs that the thousands selectors reached by way of one office has a traffic distribution amongst the various levels different than the traffic distribution of the thousands selectors of the other offices. This difference may be known incorrectly or not at all before the installation is made and may become known quantitatively only after a traffic study is made with the system in actual operation. It also often happens that while a study reveals that one office offers a traffic on one level that is heavier than was anticipated, another office whose selectors are located on another "bay" has a traffic on the same level which is correspondingly lighter than was anticipated. When this condition arises, it is merely necessary to adjust the traffic on the level in question between the selectors of these two offices only. In case the switches of these two offices are located on adjacent "bays", the re-distribution of traffic is ordinarily effected through the series tie cables or the tie cables such as the series tie cable 272, Figs. 8 and 9, which extend only between adjacent "bays". If the switches in question, however, are located on "bays" which are not adjacent to each other, the re-distribution is made through the multiple

tie cable such as tie cable 271, Figs. 8 and 9, which is multiplied through all the "bays" of the group. This permits the change to be made without re-grouping the bank and trunk cables on the level in question all along the line between the two "bays", as would be necessary in case the traffic change were effected through the series tie cables.

What is claimed is:

1. A distributing frame comprising substantially parallel rows of terminal strips, terminals mounted in said strips and protruding outward therefrom on the front and rear thereof, certain of said terminals being multiplied together throughout a plurality of said strips by conductors which extend along the front of said frame, other terminals mounted on said frame, outgoing conductors secured to said other terminals, and jumpers connected between the rear of said multiply connected terminals to certain ones of said other terminals.

2. A distributing frame having substantially parallel terminal strips mounted thereon, terminals in said strips and extending outward from the front and rear thereof, certain ones of said terminals being strapped together in rows substantially at right angles to said strips by conductors secured to said terminals on the front of said strips, two points of access on each terminal at the rear of the strip in which it is fastened, incoming conductors connected to each of said terminals at one of said points of access, and outgoing jumpers connected to certain of said terminals in each multiply connected row, each of said jumpers being connected to the other of said two points of access.

3. A "bay" of switches, a distributing frame therefor, the "shelves" of switches in said bay being connected in groups on said frame as regards one level of bank contacts, "trunk cables" terminating on said frame, and jumpers connecting said groups with said trunk cables.

4. A plurality of "bays" of switches, a distributing frame for each "bay", and "series" and "multiple tie cables" extending between said "bays" to combine them into a single unit.

5. A distributing frame having sets of contacts arranged in vertical and horizontal rows, a group of normal position automatic selector switches associated with each horizontal row, certain of said contact sets in one horizontal row being multiplied with contact sets in one or more other horizontal rows, the banks of the switches in each of said groups being multiplied together straight, and a cable connecting one switch bank in each group to its associated horizontal row of contact sets, certain conductors in certain of said cables transposed as regards their connection with the contact sets

in order to even up the traffic amongst the various contact sets multiply connected on said frame.

6. In a distributing frame, pin terminals of two different classes, the terminals of one class being arranged in vertical rows, a straight bare wire connecting the terminals of each vertical row on the front of the frame, and a jumper wire on the rear of the frame connecting one terminal of each vertical row with a terminal of the other class.

7. In a distributing frame, pin terminals of one class disposed horizontally and arranged in vertical and horizontal rows, pin terminals of another class arranged in a group apart from the terminals of the first class, straight bare wires running vertically up the front of the frame, one wire for each vertical row of terminals, said wires serving to multiple together the several horizontal rows of terminals of the first class, and jumper wires on the rear of said frame connecting the terminals of one of said horizontal rows with the group of terminals of the second class.

8. A distributing frame comprising two vertical supports spaced apart, a series of insulating strips extending horizontally between said supports and secured thereto, a plurality of pin terminals extending horizontally through each of said strips from front to rear, each pin including a front portion to which a multiple wire may be soldered and a rear portion notched in two places for the attachment of a bank wire and a jumper wire, a second series of insulating strips extending across said supports, each strip having two series of perforations, terminal blocks mounted on the front of the strips of said second series, and a row of vertical pin terminals extending through each block with their ends in alignment with the perforations in two of said series.

9. An automatic switchboard section comprising a rack of switches and a distributing frame, said rack having a plurality of shelves of switches, bank terminals on said frame arranged in groups, groups of trunk terminals on said frame, cables extending from said shelves of switches to said groups of bank terminals, trunk cables connected to said groups of trunk terminals, sets of conductors connecting the groups of bank terminals to form major groups of bank terminals, and jumpers connecting each major group of bank terminals with a group of trunk terminals.

10. An automatic switchboard section comprising two parallel racks of switches and a distributing frame, each rack having a plurality of shelves of switches, groups of bank terminals on said frame, groups of trunk terminals on said frame, cables extending from the shelves of switches on one rack to one end of said frame and terminating on

the odd numbered groups of bank terminals, other cables extending from the shelves of switches on the other rack to the other end of said frame and terminating on the even numbered groups of bank terminals, trunk cables connected to said groups of trunk terminals, sets of conductors connecting groups of bank terminals to form major groups of bank terminals, certain major groups each comprising both odd and even numbered groups, and jumpers connecting each major group of bank terminals with a group of trunk terminals.

11. An automatic switchboard section comprising two parallel racks, each having a plurality of superimposed shelves of switches, a distributing frame spaced away from said racks at one end and extending at right angles thereto, the opposite ends of said frame being substantially in alignment with said two racks, respectively, and a rectangular framework at the top holding said racks and frame in position.

12. In an automatic switchboard section, an upright panel shaped distributing frame, two parallel switch racks extending at right angles to said frame and spaced apart a distance approximately equal to the width of said frame, means connecting said racks and frame together at the top, switch bank cable terminals on one portion of said frame, trunk cable terminals on another portion of said frame, and jumpers connecting certain of said bank cable terminals with certain of said trunk cable terminals.

13. In an automatic switchboard section, an upright panel shaped distributing frame, two parallel switch racks extending at right angles to said frame and spaced apart a distance approximately equal to the width of said frame, means connecting said racks and frame together at the top, switch bank cable terminals on one portion of said frame, trunk cable terminals on another portion of said frame, jumpers connecting certain of said bank cable terminals with certain of said trunk cable terminals, and a vertical row of jumper rings on each rack for holding the jumpers in orderly groups away from the back of said frame.

14. In an automatic switchboard section, a distributing frame, two parallel switch racks adjacent thereto extending at right angles to said frame and spaced apart a distance approximately equal to the width of said frame, switch bank cable terminals on one portion of said frame, bank cables extending from said racks to said terminals, trunk cable terminals on another portion of said frame, and jumpers connecting certain of said bank cable terminals with certain of said trunk cable terminals.

15. In an automatic switchboard section, a distributing frame, a switch rack adjacent thereto extending at right angles to said

- frame, switch bank cable terminals on one portion of said frame, bank cables extending from said rack to said terminals, trunk cable terminals on another portion of said frame, and jumpers connecting certain of said bank cable terminals with certain of said trunk cable terminals. 5
16. In an automatic switchboard section, two switch racks spaced apart, a distributing frame adjoining said racks, switch bank cable terminals on one portion of the frame, bank cables extending from said racks to said terminals, trunk cable terminals on another portion of said frame, and jumpers connecting certain of said bank cable terminals with certain of said trunk cable terminals. 10
17. In an automatic switchboard section, a distributing frame, a switch rack, switch bank cable terminals on one portion of said frame, bank cables extending from said rack to said terminals, trunk cable terminals on another portion of said frame, and jumpers connecting certain of said bank cable terminals with certain of said trunk cable terminals. 15
18. In an automatic switchboard section, a distributing frame, two parallel switch racks extending at right angles to said frame and spaced apart a distance approximately equal to the width of said frame, switch bank cable terminals on one portion of said frame, trunk cable terminals on another portion of said frame, jumpers connecting certain of said bank cable terminals with certain of said trunk cable terminals, and jumper rings on each rack for holding the jumpers in orderly groups away from said frame. 20
19. In an automatic switchboard section, a distributing frame, two parallel switch racks extending at right angles to said frame, switch bank cable terminals on one portion of said frame, cables extending from said terminals to said racks, trunk cable terminals on another portion of said frame, jumpers connecting certain of said bank cable terminals with certain of said trunk cable terminals, and a row of jumper rings for holding the jumpers in orderly groups away from said frame. 25
20. In an automatic switchboard section, a distributing frame, a switch rack extending at right angles to said frame, switch bank cable terminals on one portion of said frame, cables extending from said terminals to said rack, trunk cable terminals on another portion of said frame, jumpers connecting certain of said bank cable terminals with certain of said trunk cable terminals, and jumper rings for holding the jumpers in orderly groups away from said frame. 30
21. In an automatic switchboard section, a distributing frame, two switch racks, switch bank cable terminals on one portion of said frame, cables connecting said terminals to said racks, trunk cable terminals on another portion of said frame, jumpers connecting certain of said bank cable terminals with certain of said trunk cable terminals, and a row of jumper rings for holding the jumpers in orderly groups away from said frame. 35
22. An automatic switchboard section comprising two parallel racks, each having a plurality of superimposed shelves of switches, means for cross connecting contacts of various switches, said means including a distributing frame the opposite ends of which are adjacent both of said racks, and connections between the frame and the racks. 40
23. A connecting frame comprising a plurality of parallel rows of spaced contacts each contact extending from the front to the rear of the frame, the corresponding contacts of all of the rows being in alignment, a plurality of multi-conductor cables mounted on one side of the frame each adjacent one of said rows of contacts, the corresponding conductors of each of the cables being connected to corresponding contacts in the adjacent row, and conductors on the other side of the frame connecting corresponding contacts of certain of the rows. 45
24. A connecting frame comprising a plurality of groups of spaced parallel rows of contacts, the contacts of each row being staggered with respect to the contacts in other rows of the same group and in alignment with the contacts of corresponding rows of other groups, a plurality of multi-conductor cables mounted on one side of the frame each adjacent one of the groups of contacts, the corresponding conductors of each of the cables being connected to corresponding contacts in the adjacent group, and conductors connecting corresponding contacts of certain of the groups. 50
25. In a telephone system, a plurality of rows of automatic switches, each switch containing a plurality of rows of contacts, a plurality of trunks, means for connecting corresponding contacts of different rows of switches in multiple to desired trunks, said means comprising a distributing frame having aligned rows of contacts extending from the front to the rear thereof, said trunks being grouped in cables on one side of the frame, conductors grouped in cables on the same side of the frame connecting the last mentioned contacts with the switch contacts, conductors on the other side of the frame connecting aligned contacts of certain adjacent rows, and jumpers connecting each of said last mentioned conductors with a trunk. 55
- In witness whereof, I hereunto subscribe my name this 15th day of December, A. D. 1922.

HARLEY B. McELYEA.
